(57) **CLAIM**

The ornamental design for a luminaire lens and baffle, as shown and described.

DESCRIPTION

FIG. 1 is a perspective view of our luminaire lens and baffle design;

FIG. 2 is a bottom plan view thereof;

FIG. 3 is a top plan view thereof;

FIG. 4 is a side elevational view thereof;

FIG. 5 is a front elevational view thereof;

FIG. 6 is a side elevational view thereof;

FIG. 7 is a rear elevational view thereof;

FIG. 8 is a perspective view of a second embodiment of our luminaire lens and baffle design;

FIG. 9 is a bottom plan view thereof;

FIG. 10 is a top plan view thereof;

FIG. 11 is a side elevational view thereof;

FIG. 12 is a front elevational view thereof;

FIG. 13 is a side elevational view thereof; and,

FIG. 14 is a rear elevational view thereof.

With the exception of length, it is understood that the top, bottom, and side views of the second embodiment are identical to the first embodiment.

The broken line showing of the front, rear, sides and top of the design is included for the purpose of illustration only and forms no part of the claimed design.
